UNITED STATES PATENT OFFICE.

ROSCOE L. WANAMAKER, OF TOLEDO, OHIO.

TRAIN-DESPATCH DELIVERER.

1,306,506.

Specification of Letters Patent. Patented June 10, 1919.

Application filed June 14, 1918. Serial No. 240,013.

To all whom it may concern:

Be it known that I, ROSCOE L. WANAMAKER, a citizen of the United States, and a resident of Toledo, in the county of Lucas and State of Ohio, have invented a certain new and useful Train-Despatch Deliverer; and I do hereby declare the following to be a full, clear, and exact description of the invention, such as will enable others skilled in the art to which it appertains to make and use the same, reference being had to the accompanying drawing, and to the characters of reference marked thereon, which form a part of this specification.

15 My invention has for its object to provide a means whereby a message may be delivered to the trainmen while the train is in motion. It particularly has for its object to provide a simple means to which a paper having the message may be attached and may be received by the trainmen and may then be thrown to the ground after the paper having the passage is removed, and one which will readily roll from the moving 20 train without bounding back underneath the wheels of the train and being injured. It also has for its object an efficient means whereby the despatch carrier will be held in proper position and one which may be readily removed from the mechanism for supporting the carrier.

25 Structures containing the invention may partake of different forms. I have selected a structure containing the invention as illustrative of such structures and shall describe it hereinafter. The construction selected is illustrated in the accompanying drawings.

30 Figure 1 of the drawings illustrates the despatch carrier supported in the vicinity of the track. Fig. 2 illustrates an edge view of one of the supporting parts. Fig. 3 illustrates an end view of the spring members that support the despatch carrier. Fig. 4 illustrates an enlarged broken view of the 35 despatch carrier. Fig. 5 illustrates the end of the despatch clip for holding the despatch.

1, Fig. 1, is a standard or post that may be secured to the cross ties 2 by suitable 40 means, such as the bolts 3. The despatch carriers are mounted so that they will be near the track 4 and so that the train will pass about a foot from the despatch carriers.

45 The despatch carriers are made in the form of a hoop 5. Each is provided with a clip 6 for securing the despatch to the hoop.

The spring clip 6 is preferably made of spring steel and is secured to the hoop at one end 7. The other end of the clip is provided with a slot 8 which is depressed so as to form a lip that extends crosswise the side of the hoop as shown in Fig. 4. The clip 6 presses throughout its major portion against the surface of the hoop and so that when a message is slipped under the lip 9 it will be pressed against the hoop body by the clip 6. The sides of the slotted portion pass down across the sides of the hoop body and prevent the escape of the message.

The hoop 5 is also provided with a block 10 which has a square cross section and is the part of the hoop that is held when the despatch carrier is placed in position to deliver the message to the train. The standard 1 is provided with one or more pivoted 75 levers 11 that are secured to the standard 1 by the pins 12 about which the levers 11 may be rotated, movement of the levers 11, however, being limited by the stops 13. The arms of the lever on the track side are counterbalanced by weights 14 located on the opposite side of the standard 1 and so as to raise the arms when the despatch carriers are removed from the other ends of the levers. The levers 11 are provided with 85 spring members 15 which are bolted to the ends of the levers 11 by the bolts 16.

The spring members 15 are also pressed toward each other and the ends of the levers 11 by means of the springs 17 which surround the bolts 18 that pass through the arms 11 and the spring members or plates 15. The blocks 10 have a thickness which is greater than the thickness of the arms 11 and consequently when the blocks 10 are inserted between the spring members 15 they are spring pressed by the elasticity of the spring members 15 and the springs 17. The upper corners 19 of the spring members or plates 15 are flared outward so that the block 10 may be inserted by pushing it down between the flared corners 19 and then turning the lower end of the block 10 down so as to bring the block into a vertical position. This will wedge apart the outer edge 105 of the spring members 15 and the block 10 will be securely clamped in position, whereby the loops will be held in the despatch delivering position. In removing the hoops 5 from the arms 11, the outer side of the hoops 110 are carried forward by being seized by the trainmen on the train. The outer ends of

the spring plates 15 being flared outward, the block 10 will be rotated. The corner 20 of the block will engage the curved portion of one of the members 15 and consequently 5 the opposite corner 21 will wedge the spring members 15 apart until the block is rolled out from between the spring members 15, whereupon the hoops will be liberated from the arm 11. The springs 17 that surround 10 the pins 18 permit considerable movement of the outer ends of the springs 15 and yet the springs 17 coact to yieldingly hold the hoops in the plane of rotation of the levers 11. The despatch may then be removed 15 from the hoop and the hoop may be dropped edgewise to the ground and the movement of the train will cause the hoop to roll on the ground, and if the hoop is placed relative to the direction of the moving of the 20 train so that the plane of the hoop makes an angle to the track, and so that the forward end of the hoop will be farthest from the track, that is, farthest from the side of the car or engine and the hoop is dropped, 25 the hoop will roll the direction that the train is moving and away from the train.

When the despatch carriers are removed

from the levers 11, the weights 14 will cause the arms to lift away from the tracks.

30

I claim:—

1. In a train despatch deliverer, a hoop, a block secured to the hoop and located substantially within line of the hoop, and having sides parallel with the sides of the hoop, a pair of spring pressed members for clamping the sides of the block, the spring pressed members having means for ejecting the block from between them when the block is rotated.

35

2. In a train despatch deliverer, a circular hoop member, a block contained substantially within the circle of the hoop and forming with the hoop the completion of the circle, spring pressed members for holding the hoop in position and for clamping the sides of the block, the spring pressed members having outwardly curved lips for engaging one or the other of the edges of the block to eject the block from between the 40 springs when the block is rotated.

45

In testimony whereof I have hereunto signed my name to this specification.
